UNITED STATES PATENT OFFICE.

HEMAN GARDINER, OF NEW YORK, N. Y.

QUARTZ-CRUSHER.

Specification of Letters Patent No. 11,219, dated July 4, 1854.

To all whom it may concern:

Be it known that I, HEMAN GARDINER, of the city, county, and State of New York, have invented certain new and useful Improvements in Machinery for Crushing Quartz and Ore; and I do hereby declare that the following is a full, clear, and exact description of the same, reference being had to the accompanying drawings, forming 10 part of this specification, in which—

Figure 1, is a front elevation, partly sectional, of a machine constructed according to my invention. Fig. 2, is a vertical section of the same through the center from 15 back to front. Fig. 3, is a horizontal section of the same, in the line, x, x , of Fig. 1.

Similar letters of reference indicate corresponding parts in the several figures.

In this machinery, the grinding operation 20 is performed by balls in a basin, which has a rolling motion.

My invention consists, firstly, in a certain method of supporting and giving the desired rolling motion to the basin, whereby 25 much of the heavy frame-work necessary in other machines, which employ a basin and balls, is dispensed with, and the construction of the working parts is simplified.

My invention consists, secondly, in the 30 employment within the basin, in addition to the usual ball which is left to run perfectly free, of a ball which is suspended in a certain manner from above the basin, so as to revolve around the axis thereof, and at the 35 same time to rotate upon an axis of its own, and to remain in contact with an inclined portion of the bottom of the basin in rear of the free ball.

To enable those skilled in the art to make 40 and use my invention, I will proceed to describe its construction and operation.

A, represents a solid foundation or bed, which may be of timber or masonry, resting or built upon the ground, and having a level 45 surface.

B, B, are two timber uprights, supporting a cross-piece, C, over the foundation or bed, A. At the center of the cross-piece, is suspended a stationary vertical shaft, D, at 50 whose lower end is a knob, b, of nearly hemispherical form.

E, represents the basin in which the preparatory crushing process is performed, which is of substantially similar form to 55 the basin commonly employed with a ball in it, except that at the center there is an

inverted cup, a, which fits loosely over the knob, b, on the shaft, D, which would suspend the basin if the latter were left free without any ball, at some distance above the bed, A. 60

F, is the ball similar to that generally employed in the basin, being left to roll quite freely; it weighs down one side of the basin and causes it to bear upon the bed, which 65 supports it and part of the weight of the pan, leaving only a part of the weight of the latter suspended on the shaft.

At about the middle of the length of the shaft, there is a stationary collar, c, which 70 supports a loose pulley, G. To this pulley is attached an arm, H, to which is attached a roller, r, whose periphery bears upon a path, d, which extends all around the rim of the basin. This roller bears upon the path, d, 75 near its lowest part, and when the pulley, G, receives a rotary motion, the roller running around the path, d, depresses all sides of the basin in turn, and gives the basin a rolling motion on the bed, A; any tendency of the 80 basin to rotate, being checked by a stud, e, on one side of the basin, which carries a friction roller, and bears against one of the uprights, B. The rolling motion of the basin causes this stud to work up and down with 85 the friction roller, in contact with the upright. The motion given to the basin resembles, in a great degree, that given to the basins of other machines; but, this basin rests on a firm bed and is perfectly steady, while 90 all those basins are suspended, and their great weight, with the greater weight of the ball and contents, cause them when in motion, to produce such excessive vibration of the framing that it is practically almost im- 95

possible to make it of sufficient strength, and the greatest weight being always on one side of the shaft of the basin, causes the bearings to wear unevenly, and the entire machine to get out of truth. 100

I, is what I term the supplemental ball, which is of about the same size as the ball, F. It is bored through its axis to fit loosely on a shaft, i, which is suspended or attached by two rods or chains, J, J, from the pulley, G, or instead of being bored to fit the shaft, may be otherwise provided with the means of suspending it, so that it may rotate on its axis. The point in the pulley at which the rods or chains are attached, is above the center of the track of the ball, and opposite, or nearly so, to the arm, H. The rods or 105 110

chains, J, J, are of such length as to allow the ball, I, to assume a position about half-way between the highest and lowest parts of the basin, and, considering the direction in 5 which the pulley revolves, (indicated by an arrow in Fig. 3), the ball, I, should be in rear of the ball, F. This position of the supplementary ball brings it in contact with the steepest part of the incline of the bottom of the basin. The revolution of the 10 supplementary ball around the axis of the basin in contact with the bottom of the basin, or with the contents thereof, causes it to revolve on the shaft, i, and as it follows 15 the ball, F, it comes in contact with the quartz or ore, where there is not so large a body as at the lowest part of the basin, and grinds it.

The quartz or ore is intended to be supplied to the machine continuously with a 20 stream of water, and when ground to a suitable degree of fineness, will be washed away at the spout f, into any suitable receptacle, or received from the said spout by an amalgamating apparatus. The quarts may however be ground dry, and the pan be charged 25

from time to time, and discharged when the contents are all ground.

What I claim as my invention, and desire to secure by Letters Patent, is—

30

1. Suspending the basin, E, at the center, by a fixed shaft, D, above a bed, A, in the manner substantially as described, whereby while every part of its circumference is in turn depressed by an arm, H, and roller, r, 35 or their equivalents revolving on the shaft, the lowest part of the basin, where the greatest weight is, always rests upon the bed, and the shaft is relieved of the greater portion of the weight of the basin and its 40

contents.

2. The supplemental ball, I, suspended or attached in the manner substantially as described, from the pulley, G, or its equivalent, revolving above the basin, so that it is 45 always in contact with the inclined part of the basin where the quartz or ore is most thinly distributed.

HEMAN GARDINER.
